UNITED STATES PATENT OFFICE.

WILL YERGER, OF WEST PHILADELPHIA, PENNSYLVANIA.

TRIMMER.

Application filed December 10, 1924. Serial No. 755,052.

This invention relates to a trimmer, the general object of the invention being to provide a simple device which can be held by one hand and used for trimming hedges, 5 lawns and the like, with means for operating the cutting member either from a motor suspended on the person or by a hand wheel attached to the person and rotated by the free hand of the person.

10 This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying drawings wherein like characters denote 20 like or corresponding parts throughout the several views, and in which:—

Figure 1 is a plan view of the trimmer.

Figure 2 is a sectional view through the trimmer.

25 Figure 3 is a perspective view of the cover plate.

Figure 4 is an enlarged plan view with parts in section.

Figure 5 is a similar view but showing the 30 driving means.

Figure 6 is a section on line 9—9 of Figure 5.

Figure 7 is a bottom plan view.

Figure 8 is an edge view.

35 In these views, 1 indicates a frame having a handle 2, and formed with an arcuate portion 1'. A bottom plate 3 is bolted to the frame and which is formed with the fingers 4 which cooperate with the rotary cutter 5 which has a pair of curved cutting arms, as 40 shown. This cutter is fastened to the lower end of a sleeve 6 which is carried by a bolt 7 passing through the bottom plate and through the frame and through an enlargement 45 formed on the cover plate 9 which is held to the frame by the same bolts which hold the bottom plate to the frame. A worm wheel 10 is also fastened to the sleeve 6 and these parts are held on the bolt by the

50 nuts 11. A worm 12 is rotatably arranged in the space formed by the enlargement 8 and meshes with the gear 10 and this worm is connected by a flexible shaft 13 with a motor 14 which is attached to a harness so that 55 the motor can be carried by a person using the trimmer. If desired, the flexible shaft

can be attached to a worm 16 which meshes with a worm wheel 17, to the shaft of which a hand wheel 18 is connected, so that the trimmer can be operated by hand. In this 60 case the frame 19 which carries the hand operated means is connected with the belt of the harness. The flexible shaft is enclosed in a casing 20 as usual. A sheath may be provided for the fingers when the device is 65 not in use.

From the foregoing it will be seen that as the revolving cutter passes over the fingers it will bring the material being acted upon 70 between itself and the cutting edges of the fingers so that the material will be cut. The under face of the plate 3 is provided with tapering grooves 22 which communicate with the spaces between the fingers so that the trimmer can pass over the stumps of the 75 material being cut without difficulty. The curved arms of the revolving cutter passing over the fingers will insure quick and efficient cutting of the material as it passes between the fingers. As before stated, the 80 trimmer can be operated by a motor, as shown in Figure 1 or by hand operated means.

It is though from the foregoing description that the advantages and novel features 85 of my invention will be readily apparent.

I desire it to be understood that I may make changes in the construction and in the combination and arrangement of the several parts, provided that such changes fall 90 within the scope of the appended claim.

What I claim is:—

A device of the character described comprising a frame, a handle attached to the frame, a bottom plate on the frame formed 95 with a plurality of spaced fingers, an arcuate housing at the inner end of the plate, a removable cover plate for the frame having an enlargement, a bolt extending through the bottom plate and through the enlargement, 100 a sleeve mounted on the bolt, a worm gear mounted upon the sleeve, nuts threaded on the upper end of the bolt and bearing against the sleeve, a driven shaft extending through the enlargement, a worm upon said 105 shaft adapted to mesh with the first worm, and a rotary cutter carried by the inner end of the sleeve and rotatable over the fingers as and for the purpose specified.

In testimony whereof I affix my signature. 110

WILL YERGER.
